UNITED STATES PATENT OFFICE.

JOHN J. MAHONY, OF SAN FRANCISCO, CALIFORNIA.

DUMB-WAITER STOP.

SPECIFICATION forming part of Letters Patent No. 367,152, dated July 26, 1887.

Application filed May 11, 1887. Serial No. 237,905. (No model.)

To all whom it may concern:

Be it known that I, JOHN J. MAHONY, of the city and county of San Francisco, State of California, have invented an Improvement in 5 Dumb-Waiter Stops; and I hereby declare the following to be a full, clear, and exact description of the same.

My invention relates to that class of reciprocating elevators commonly known, from 10 the use to which they are put, as "dumb-waiters," and to certain improvements with respect to the mechanism by which they are stopped at any desired point in the course of their travel.

15 These improvements are of the same general nature as those shown in my Patent No. 356,948, dated February 1, 1887; but they are herein greatly simplified, many of the parts being omitted and all springs being dispensed 20 with.

25 My invention consists in the combination and arrangement of the pivoted gravity-catch, the rack or notched strip with which it engages, and the pivoted gravity trip-lever, all of which I shall hereinafter fully describe.

The general object of my invention is to 30 provide simple and effective means for positively stopping the waiter at points at which it is intended to rest, thereby doing away with the necessity of friction to effect the result.

The particular object is to provide mechanism of a simple and effective character, which will operate certainly and without noise.

Referring to the accompanying drawings for 35 a more complete explanation of my invention, Figure 1 shows the stop in position going up. Fig. 2 shows the stop in position of rest. Fig. 3 shows the device raised to clear the catch. Fig. 4 shows it descending. Fig. 5 is a horizontal section. Fig. 6 is a detail of a portion 40 of the lever F, showing the shoulder f'.

A is the well or shaft, having the guides a.

B is the dumb-waiter, mounted in the well and adapted to move up and down therein. 45 The waiter is suspended by means of a rope, which may be supposed to extend upwardly, and after passing over a suitable pulley to extend down again, and to be provided with a weight, as usual.

50 To the side of the guide a (or otherwise secured in the well or shaft) is fixed a rack or strip, D, which has on one edge an inclined

notch, d, the base of which terminates in a straight shoulder, d'. The lower end of the strip is beveled at d², and its upper end has its 55 face inclined backwardly, as shown at d³. To the side of the waiter is secured a plate, e, to which is pivoted at e' the catch-lever E, which is of an elbow or bell-crank shape, its lower arm acting as the catch and its upper arm being provided with a weight, W, the tendency of which is to hold the lower end of the lever 60 against the rack-strip; but this tendency is limited by a stop, e².

Pivoted at f upon the lower arm of the lever 65 E is the trip-lever F, the outer end of which has a weight, w, the tendency of which is to throw the other end up; but this movement, as well as the reverse movement of said trip-lever, is limited by reason of the shoulder f' 70 on the weight end coming in contact with the edge of the catch-lever E below or above, as the case may be.

The operation is as follows, supposing the waiter to be in the position shown in Fig. 1: 75 It will be seen that the catch-lever E is thrown over against its stop e² and the trip is raised by its weight, so that its shoulder f' is stopped by the edge of the catch-lever below. Now, 80 upon moving the waiter up the operative end of the trip-lever comes in contact with the beveled lower end of the strip D, and is turned on its pivot until limited by its shoulder f' coming in contact with the edge of the catch-lever above, and in this position its end lies practically flush with the edge of the catch-lever. 85 Both levers now pass the lower end of the strip D, and when they reach the shoulder d' of said strip both are thrown into it by the action of the weight W of the catch-lever, the 90 lower end of said lever resting in the shoulder, and thereby supporting the waiter, as is shown in Fig. 2. Now, in order to lower the waiter it is first moved up still higher until both levers are free of the strip D, which 95 has prevented the trip-lever from falling back, whereupon said lever being now free falls back to its original position and the catch-lever is limited by the stop e², so as not to be in the line of the upper end of the strip, which 100 for this purpose is slightly cut back at d³. Now, the waiter is started down, and the end of the trip-lever coming in contact with the upper end of the strip and being stopped by

the engagement of its shoulder *f* with the edge of the catch-lever is forced over to one side and carries the catch-lever with it, so that as it passes down the face of the strip it holds the 5 lower end of said catch-lever away from the strip and allows it to pass the shoulder *d* without touching. As soon as the lower end of the strip has been passed, the parts return to position under the influence of their respective 10 weights.

Having thus described my invention, what I claim as new, and desire to secure by Letters Patent, is—

1. In combination with a dumb-waiter mounted and suspended so as to be reciprocated, a strip in the well or shaft in which the waiter moves, having a shoulder on its inner face, a pivoted weighted lever secured to the waiter and having its lower end adapted to 15 engage the shoulder of the strip, thereby supporting the waiter, and an oscillating weighted trip-lever connected with the catch-lever and adapted to come in contact with the face of the strip, whereby it forces the catch-lever 20 over from the face of the strip, thereby allowing its descent, substantially as herein described.
2. In combination with a reciprocating dumb-waiter, the mechanism for supporting 25 and relieving it, consisting of a strip in the well or shaft, having a shouldered face, a vi-

brating elbow or bell-crank catch-lever carried by the waiter and having one end weighted, whereby its other end is made to play against and to engage the shouldered face of the strip 35 and to support the waiter thereby, and an oscillating trip-lever pivoted to the catch-lever, and having one end weighted, whereby its other end is made to play against the face of the strip to force and hold the catch-lever 40 from its engagement, substantially as herein described.

3. The dumb-waiter stop consisting of the vibrating weighted catch-lever pivoted to the waiter, the oscillating weighted trip-lever 45 pivoted to the catch-lever and having a shoulder by which its movement is limited, the fixed stop by which the movement of the catch-lever is limited, and the rack-strip D in the well or shaft in which the waiter moves, 50 having a shoulder with which the catch-lever engages to support the waiter and a face against which the trip-lever plays to free the catch-lever of the shoulder, substantially as herein described. 55

In witness whereof I have hereunto set my hand.

JOHN J. MAHONY.
